DESIGN FOR A GAME BOARD

Roland J. Velz, Colorado Springs, Colo.

Application October 20, 1939, Serial No. 87,770

Term of patent 3½ years

To all whom it may concern:

Be it known that I, Roland J. Velz, a citizen of the United States, residing at Colorado Springs, in the county of El Paso and State of Colorado, have invented a new, original, and ornamental Design for Game Boards, of which the following is a specification, reference being had to the accompanying drawing, forming a part thereof.

In the drawing:

Fig. 1 is a plan view of a game board showing my new design; and Fig. 2 is a sectional view thereof, taken on the line 2—2, Fig. 1.

I claim:

The ornamental design for a game board, as shown.
